(57) CLAIM

The ornamental design for an integrated truck tailgate cover and game apparatus, as shown and described.

DESCRIPTION

FIG. 1 is a top, left, rear side perspective view of an integrated truck tailgate liner and game apparatus, the right side being a mirror image thereof;

FIG. 2 is a bottom plan view thereof; and,

FIG. 3 is a front elevation view thereof.

The broken lines (if any) are provided for illustrative purposes only and form no part of the claimed design.
